UNITED STATES PATENT OFFICE.

WILLIAM ERVIN, OF ARGENTINE, KANSAS.

BRACKET-CLAMP FOR SHINGLING.

SPECIFICATION forming part of Letters Patent No. 337,825, dated March 16, 1886.

Application filed January 7, 1886. Serial No. 187,850. (No model.)

To all whom it may concern:

Be it known that I, WILLIAM ERVIN, a citizen of the United States, residing at Argentine, in the county of Wyandotte and State of Kansas, have invented a new and useful Roofing-Clamp, of which the following is a specification.

My invention relates to bracket-clamps for supporting a scaffold in roofing; and it is my object to provide a bracket-clamp of simple construction, of as few parts as possible, and yet be durable and economical.

In the drawings, Figure 1 is a side view in section of my invention in position on a shingle roof. Fig. 2 is a front elevation of my bracket-clamp. Fig. 3 is a perspective view.

My bracket-clamp, as shown in the drawings, is constructed of two pieces, the bracket A, having the elongated tongue *a*, and the cam-lever B, pivoted or fulcrumed in the bracket at *b*. The tongue *a* is flat on its under side and beveled on its upper side near the end, as shown in Figs. 1 and 3. The cam-shaped part of the lever B is beveled to an edge, as shown in Figs. 1 and 3. I use steel, cast-iron, or other material suitable in manufacturing my bracket-clamp.

To adjust the bracket to the roof, the tongue *a* is inserted under the butt-end or loose end 30 of the shingle, with the lever perpendicular, or in the position shown in Fig. 2; and to clamp it to the shingle the lever B is pressed over to the right until the beveled edge of the

cam-shaped part thereof presses tightly and bites into the shingle, as shown in the drawings.

It is evident that the lever B may have diametrically opposite cam-shaped projections so formed that the bracket could be clamped to the shingle by pressing the lever B either to 40 the right or left.

In brackets heretofore constructed the clamping-lever has, so far as I am aware, been arranged to swing up and down relative to the slope of the roof, with the effect often of pushing down or out a little way the tang of the bracket from under the shingle. My device avoids this, as also the danger of splitting the shingle.

I claim—

1. In a shingle-bracket, the combination of a bracket having a part to run under the butt of a shingle, and a cam-lever swinging to the right or left to clamp the same to the shingle.

2. A bracket-clamp for roofing, consisting 55 of a bracket, A, formed out of a single piece of material having an elongated tongue, *a*, and cam-lever B, pivoted or fulcrumed thereto, substantially as shown and described.

In testimony whereof I have hereunto subscribed my name this 19th day of December, 1885.

WILLIAM ERVIN.
